UNITED STATES PATENT OFFICE.

FRANK W. ADDINGTON, OF RICHMOND, INDIANA.

PNEUMATIC WHEEL.

1,173,156.

Specification of Letters Patent.

Patented Feb. 29, 1916.

Application filed January 18, 1915. Serial No. 2,783.

To all whom it may concern:

Be it known that I, FRANK W. ADDINGTON, a citizen of the United States, and a resident of the city of Richmond, in the county of Wayne and State of Indiana, have invented a new and useful Construction in Pneumatic Wheels, of which the following is a full, clear, and comprehensive description and specification, being such as will enable others 10 to make and use the same with exactitude.

My invention relates to pneumatic vehicle-wheels wherein the predominant feature is that the air container is located at a distance inward from the periphery of the wheel, 15 where it can not become punctured by objects with which the wheel may come in contact, and reducing the wear and deterioration to the minimum.

The object of my invention, broadly 20 speaking, is to provide a pneumatic wheel which will be strong and durable in construction, neat and attractive in appearance, easily assembled or taken apart, adapted to provide a maximum of resiliency in operation 25 with a minimum of wear upon the parts thereof, and which can be manufactured and sold and maintained at a comparatively low price.

Other minor objects and particular advantages of my invention will be brought 30 out and made manifest in the course of the following description, and that which is new will be correlated in the appended claim which terminates this specification.

35 The preferred manner for accomplishing the desideratum in a practical manner is shown in the accompanying drawings, in which—

Figure 1 is a front face view or elevation 40 of my wheel, as it would appear in actual practice. Fig. 2 is the same as Fig. 1 except that the front disk is removed, showing the interior of the wheel and the various parts thereof. Fig. 3 is a perspective view of one 45 of the segment members of the movable plunger. Fig. 4 is a perspective detail view of a portion of the inner tube and its envelop. Fig. 5 is a central section as taken through the wheel on the line 5—5 of Fig. 1. Fig. 6 is an inner face view of one of the 50 inclosing disks. And Fig. 7 is a front elevation of a slightly modified form, in which the plunger is formed in one part, the front disk being shown as broken away in order to 55 show the modified plunger.

Similar indices denote like parts throughout the several views.

In order that the construction, the operation, and the advantages of my invention may be fully understood and appreciated, I 60 will now take up a detailed description thereof, in which I will set forth the invention as comprehensively as I may.

Referring now to the drawings in detail, 65 numeral 1 denotes the hub, which may be of any ordinary form or construction desired. Radiating out from around the hub, at right-angles thereto, is the flange 2. Carried by the periphery of the flange 2 is the concavo-convex channel-rim 3, whose channel faces 70 outward and extends entirely around the hub. The rim 3, the flange 2, together being substantially Y-shape in cross section, and the rim 3, the flange 2, and the hub 1 may be formed integral with each other, as shown 75 in Fig. 5, or they may be made of separate parts secured together. The movable plunger is made up of a plurality of segmental portions, one of which is shown in Fig. 3, which are all identical with each other, and 80 each comprises a flat stem A, which is of trapezium shape; the outer head portion B; and the inner concavo-convex portion which forms the outer channel rim C, the latter being similar but oppositely disposed to the 85 rim 3 from which they are spaced as shown. The rims C of the plunger together form a channel entirely around the channel of the rim 3 to receive the envelop 6, as shown in Fig. 5.

Two radial slots, a and a', are formed 90 through each of the members of the plunger, as shown in Figs. 1 and 3.

Numerals 4 and 5 denote the two inclosing 95 disks, which are identical with each other, each having a central aperture b therethrough as shown in Fig. 6, which aperture is larger than is the diameter of the hub 1 which is disposed therethrough. The central and the outer portions of each of the 100 disks is formed flat and they are parallel and in alinement with each other, while between these parts, that is about midway between the center and the periphery of each disk, there is an outwardly curved portion 105 forming an annular channel e, Fig. 6, which corresponds to the curvature of the rims 3 and C, as shown in Fig. 5. Fitting around in the circular inclosure formed by the rims 3 and C is the envelop 6, which may be 110

formed of leather or other flexible material of strength, which is adapted to open out along its inner periphery, where the edges thereof may be detachably secured together 5 by means of lacing 7. Fitting in and inclosed by the envelop is the compressed-air tube 8, which is provided with an air inlet valve 9. Formed through the inner portion of the disks 4 and 5 are the bolt apertures *f*, each 10 to receive one of the bolts 10, which bolts also pass through corresponding apertures formed through the flange 2, whereby the two disks are rigidly connected to the flange 2. Also formed through the outward portions 15 ~~tubes~~ of the disks 4 and 5 are the bolt apertures *h*, through which the bolts 11 are disposed which secure the disks 4 and 5 in contact with the various members of the plunger; the said bolts pass through the 20 slots *a*—*a'* of the segments of the plunger. Secured around in the channels, formed in the heads *B* of the segments of the plunger is the rubber tread 12.

Surrounding each of the bolts 11, and 15, 25 is a spacer 16, whose length is slightly more than is the thickness of the stems *A*, whereby the bolts 11, and 15, may be made tight to secure the disks 4 and 5 but without clamping them too tight against the 30 plunger, so as to prevent the plunger from moving freely.

It will now be seen that if the proper air-pressure is inserted in the tube 8 that the segments of the plunger will be forced out 35 to their limits, causing the tube 8 and the envelop 7, to be practically round in cross section, as shown in the upper part of Fig. 5. Now if weight be applied to the wheel forcing the tread 12 tightly into contact 40 with the ground 13, it is apparent that the members of the plunger will be progressively forced inward against the resiliency of the tube 8, thereby causing the weight to be carried by the air in the tube. The 45 spaces *m* and *n*, located on each side of the envelop and between the rims 3 and *C* will permit the outward expansion of the tube and envelop when weight is applied to the wheel, as shown in the lower portion of Fig. 5, thereby permitting movements similar to 50 that of a peripheral pneumatic tire.

In some instances I find it desirable to form the plunger of one integral construction 14, that is dispensing with forming the 55 plunger into segments and forming it solid,

as shown in Fig. 7. In this modified form the slots *a* and *a'* are dispensed with and in place thereof I form a plurality of comparatively large apertures *q*, dispensing with part of the bolts 11, and arranging the bolts 60 15 as in Fig. 7. In this modified form the entire plunger moves at one time between the disks 4 and 5, the apertures *q* being of such size as to allow of the required universal movement. By means of either the 65 preferred or the modified construction the load carried by the wheel will receive the full resiliency of the tube plus the resiliency of the tread 12.

In order to prevent the plunger 14 from 70 creeping I pivot it at one point, as shown at the right in Fig. 7. To do this I simply provide a radial slot *q'*, in place of the round apertures *q*, with the bolt 15' extending therethrough, this will permit the plunger 75 to move with the bolt 15' as a pivot.

Having now fully shown and described my invention, what I claim and desire to secure by Letters Patent of the United States, is—

A pneumatic wheel comprising a hub, a plurality of segmental plungers each being substantially Y-shaped in cross section, the outer and inner ends of the plungers each being channeled, the tread of the wheel 85 adapted to rest within the outer channeled portions of the plungers, a pneumatic member arranged between the inner channeled portions of the plungers and the hub of the wheel, the medial portions of the plungers 90 having elongated slots therein, plates rigidly secured to the hub of the wheel and extending radially therefrom, the medial portions of the plates adapted to inclose the pneumatic member and the inner ends of the plungers, the outer ends of the plates adapted to lie on each side of the medial portions 95 of the plungers, bolts extending through said slots and plates for slidably connecting the plates to the sections, and a spacer encircling the bolts and arranged between the plates for the purpose set forth.

In testimony whereof I have hereunto subscribed my name to this specification in the presence of two subscribing witnesses. 100 105

FRANK W. ADDINGTON.
